CLAIM

The ornamental design for a remotely operated storage vehicle, as shown and described.

DESCRIPTION

1. Remotely operated storage vehicle

FIG. 1.1 is a perspective view of a remotely operated storage vehicle showing our new design;

FIG. 1.2 is a front elevation view thereof;

FIG. 1.3 is a rear elevation view thereof;

FIG. 1.4 is a left-side view thereof;

FIG. 1.5 is a right-side view thereof; and

FIG. 1.6 is a top plan view thereof.
